UNITED STATES PATENT OFFICE.

CARL E. AKELEY, OF NEW YORK, N. Y., ASSIGNOR TO AKELEY CAMERA INC., OF NEW YORK, N. Y., A CORPORATION.

TOGGLE FOR CAMERA-TRIPODS.

1,324,781.

Specification of Letters Patent.

Patented Dec. 16, 1919.

Application filed May 20, 1918. Serial No. 235,524.

To all whom it may concern:

Be it known that I, CARL E. AKELEY, a citizen of the United States, residing at New York, county and State of New York, have 5 invented certain new and useful Improvements in Toggles for Camera-Tripods, of which the following is a full, clear, and exact description.

This invention is embodied in a tripod 10 for such devices as motion picture cameras or the like, and is an improvement on the devices shown and described in my former Patent No. 1,244,682, dated October 30, 1917.

The tripod of the patent referred to has 15 legs composed of two telescopically adjustable sections or bars, held together in proper operative relation, and secured when adjusted to the proper or desired length by toggles intermediate adjacent legs which 20 when straightened clamp together the two telescoping parts or sections of each leg.

In practical use and especially under conditions of a somewhat exacting nature, it has been found that this device was not 25 entirely adequate, as rough handling or accidental striking of the toggles by the user or by foreign bodies was liable to upset the latter and by thus freeing the leg sections from one another, permit the tripod 30 as a whole to collapse or break down.

To prevent this and to lock the straightened toggles so that they may not be accidentally upset has been the object in view in devising the attachment upon which 35 this application is based, and this I have done by using in conjunction with the toggle a short sleeve surrounding and secured to the central or intermediate member of the toggle, and carrying a pivoted latch 40 which is spring actuated and which enters a recess in one of the end members when the toggle is straightened out to lock the toggle in such straightened condition so that no ordinary knock or blow will upset it.

45 The latch has a projecting arm or lever that may be grasped by the hand to release it, when so desired, and permit the toggle to be upset by the pressure of the hand or a slight blow on the sleeve surrounding the 50 central member.

This improvement is illustrated in the accompanying drawing, in which—

Figure 1 is a view in elevation of portions

of two tripod legs, and an intermediate toggle with my improved device attached thereto and in a straightened condition.

Fig. 2 is a similar view showing the same parts with the toggle upset.

Fig. 3 is a top plan view of the toggle and its attachment.

Fig. 4 is a sectional view of the same.

Fig. 5 is a cross section of the toggle attachment on line 5—5, Fig. 4, and

Fig. 6 is a cross section of one of its members on line 6—6 of the same figure.

It will be understood that the toggle herein shown has its end members 5 and 6 pivoted to metal sleeves 7 and 8, which are secured to the rods or sections of the tripod legs 9, and surround the upper rods or sections of the same 10, forming a telescoping joint between the two.

Flexible metallic plates or blades 11 are pivoted to the rods 9 near their upper ends and have strips of leather 12 attached to them, and when the two leg sections have been adjusted to the desired relations and the toggle straightened out, the ends of the end members suitably formed for this purpose press the metal blades 11 against the upper leg sections and lock the upper and lower sections firmly together.

The toggles may be modified in character or form, but I prefer to use a solid end member 6, a central or intermediate member 13 near one end of which is pivoted the end member 6, and into which at the other end the second end member 5 is adapted to slide, being connected with it by a pin 14, working in a longitudinal slot 15.

Over the intermediate member 13 is placed and secured a sleeve 16, having projections 17, extending below said member to which is pivoted a curved arm 18, that serves as a latch, by having a turned up end 19 adapted, when the toggle is straightened, to enter a recess 20 in the solid end member 6. A spring 21 exerts on this latch lever a force tending to keep its upturned end engaged in the notch.

The toggle is straightened or set without the use of the sleeve 16, but when the latch engages with the end member 6, it is securely held in its set position. To release it the sleeve and lever 18 are grasped and the latch withdrawn from its engagement.

whereupon by forcing the sleeve down or striking it a blow with the hand the toggle is upset.

As above pointed out this device entirely 5 obviates the danger of upsetting the toggle under almost any conditions of rough usage, and the device forms a valuable addition to an otherwise highly useful and serviceable means of adjusting a tripod.

10 What I claim is:—

1. A tripod comprising in combination a plurality of upper sections, a plurality of lower sections each telescopically engaged with a corresponding one of said upper 15 sections, toggle mechanism which when straightened binds the upper sections to the lower sections, and a latch secured to one of the toggle members and adapted to engage with another of such members when said members are in their operative binding position.

2. A tripod comprising in combination a plurality of upper sections, a plurality of lower sections each telescopically engaged 25 with a corresponding one of said upper sections, toggle mechanism which when straightened binds the upper sections to the

lower sections, a latch secured to one of the toggle members and adapted to engage with another of such members when said members are in their operative binding position, and a spring acting on said latch and tending 30 to maintain it in such engagement whereby the toggle is prevented from being upset.

3. In a device of the kind described, the combination with a toggle composed of end members and an intermediate member of a spring actuated latch carried by the intermediate member and adapted to enter a recess in one of the end members when the toggle is straightened and to thereby lock the toggle in such position.

4. In a device of the kind described, the combination with a toggle composed of end 40 members and an intermediate member of a sleeve surrounding and secured to the intermediate member, a spring actuated latch lever pivoted to said sleeve and adapted to enter a recess in one of the end members 45 when the toggle is straightened and to thereby lock the toggle in such position.

In testimony whereof I affix my signature.
CARL E. AKELEY.
